VIEWER FOR PHOTOGRAPHIC IMAGES

Alex J. Weinstein, Mount Vernon, N. Y., assignor to
The Ednalite Optical Company, Inc., Peekskill, N. Y.,
a corporation of New York

Application December 11, 1956, Serial No. 44,159

Term of patent 14 years

(Cl. D61—1)

FIG. 1.

FIG. 2.

FIG. 3.

Fig. 1 is a front elevational view of a viewer for photographic images showing my new design;

Fig. 2 is a side elevational view thereof; and

Fig. 3 is a rear elevational view.

The opposite side, not shown, has substantially the same appearance as the side shown in Fig. 2. A portion of the drawing figures is diagonally lined to indicate transparency.

I claim:

The ornamental design for a viewer for photographic images, substantially as shown and described.
